UNITED STATES PATENT OFFICE

DAVID BAUM, OF LIVERMORE FALLS, MAINE

GLOVE-TURNING MECHANISM FOR GLOVE-TURNING MACHINES

Application filed January 23, 1928. Serial No. 248,856.

My invention relates to apparatus for turning gloves, by which is meant the reversing of the glove from the right to the wrong side, or vice versa.

5 The general object of my invention is to provide improved devices by which to accomplish the glove-turning operation, the parts involved being used on a glove-turning machine patented by me July 27th, 1920, No. 1,348,077.

10 In certain grades of gloves, particularly the kind having heavy leather facings, the turning operation especially at the start is quite apt to strain the material of which the 15 glove is made and often results in the necessity to re-stitch the seams.

An object I seek is to alleviate if not wholly eliminate this difficulty by employing a yielding plunger action, which action, however, 20 applying to the plungers only,—the glove supports being vertically fixed and unyielding. The flexibility of the plunger action takes care of the sudden shock incident to the engagement of the turning elements and 25 vertically immovable supports hold the glove in correct and non-distorted shape while the turning progresses.

Another object is to provide an oscillatory movement of the plungers in combination 30 with the reciprocatory action at the beginning of the turning, thus giving the tip of the glove finger a slight twist which facilitates its entry into the tubular support. This feature is especially applicable to the thumb 35 as this member is stiffer and more rigid than the fingers.

A further object is to provide, more especially for the two outer support units, a tilting action, allowing them to bend or sway 40 toward each other for the purpose of more easily inserting the ends of the supports in the finger openings of the glove and also to provide a more compact assembly of the glove-support ends over which to pull down 45 the wrist band of the glove.

Still further objects relate to the ability to readily re-position the plungers and glove-supports in their respective seats whereby gloves of various sizes and styles may be 50 accommodated, and also to the design of the

parts and the method of assembling or disassembling these elements whereby they may be quickly attached to or detached from the proper parts of the glove-turning machine.

With these and other objects in view the 55 invention consists in the novel features hereinafter described, and in the accompanying drawings in which is shown one and the preferred embodiment of my invention,—

Fig. 1 is a sectional elevation of a complete 60 glove-turning plunger assembly;

Fig. 2 is a fragmentary sectional elevation of the same, showing the plunger oscillatively as well as reciprocably mounted in its housing;

Fig. 3 is a side elevation of a plurality of 65 plunger assemblies secured to the upper, or movable bracket of the glove-turning machine;

Fig. 4 is a dual assembly, comprising a 70 plunger unit and a glove-support unit;

Fig. 5 is an end elevation of a glove-support 75 assembly;

Fig. 6 is a side elevation of the above;

Fig. 7 is a modified form of the glove 80 thumb support;

Fig. 7^a shows the application of curved thumb supports;

Figs. 8 and 9 are side and end elevations, 85 respectively, of a modified form of glove-support holder;

Fig. 10 is a sectional view taken on line 10—10, Fig. 9;

Fig. 11 is a sectional view taken on line 11—11, Fig. 5, and

Fig. 12 is a sectional view taken on line 12—12, Fig. 5.

Like character references identify similar parts in all views.

In the drawings, 1 represents the upper, 90 vertically reciprocable bracket of the glove-turning machine hereinbefore referred to as covered by U. S. Patent No. 1,348,077, and 2 the lower, fixed bracket therefor,—the glove plunger units being mounted on the former 95 and the glove supports on the latter.

In the upper bracket 1 is a longitudinal slot 3, the sides thereof, near the top, being flared outward, providing a seat 4 in which are stationed the four glove-plunger hous- 100

ings 5 with tapering sides 6 which closely fit the seat 4. The object of this construction is so as to be able to re-position the housings along the bracket seat to any desired center 5 to center distances therebetween for the purpose of accommodating different sizes of gloves. The housings are secured in their seats by the nuts 7, and to readjust their positions all that is required is to relax the nut, 10 manually slide the housings along the bracket and then retighten the nut.

Reciprocable in each housing is a plunger 9 having a reduced portion 10 on which is fixed a collar 11 operating in an enlarged bore 15 12 of the housing.

Surmounting the top of the housing and screw-threaded thereto for adjustment purposes, is a cap 13, and abutting on the top of this cap and threaded on to the portion 10 of the plunger is a nut 14. A helical spring 15 thrusts on the top of the collar 11 and on the bottom of the bore of the cap 13, thus holding the plunger normally and inertly as shown in Fig. 1. The nut 14 provides axial 20 adjustment of the plunger relative to vertical movement within the housing.

Fitting the screw-threaded portion 16 of the housing is a sleeve 17 serving as an abutment against which the collar 18 fixed on the 30 plunger may shoulder to resist the upward movement of the latter within the housing. By the use of this sleeve 17 the stroke of the plunger within the housing may be varied.

It is therefore obvious, firstly, that the 35 plunger may be adjusted to various vertical, inert positions in and with reference to the housing; secondly, that the stroke of the plunger within the housing may be varied; and thirdly, that upward movement of the 40 plunger within the housing may be resisted with greater or lesser potency,—all by the possible combination of adjustments made by the nut 14, the cap 13 and the sleeve 17.

It will be observed that the lower end of 45 the plunger, at 19, is flattened and made broader and thinner than elsewhere. This portion, which I term the turning head of the plunger, operates to draw the sides of the glove finger tips together as they enter the glove-supports and leaves more space transversely of the direction of expansion of the tubular support blades when used in conjunction with the type of glove-support which I patented May 12, 1925, No. 1,537,794, than 50 would be the case was the plunger end made of a uniform round section throughout. This increased width of the plunger end necessitates some provision to prevent the possible rotation of the plunger in the housing,— 55 otherwise, should the plunger turn, say ninety degrees, the breadth of the plunger end being too great to freely enter the glove-support width-ways of the latter, there would be a conflict between and injury to the parts when 60 they mutually engage.

I therefore provide means to control this rotation of the plungers,—preferably eliminating all rotation of the finger plungers but allowing a slight oscillation of the thumb plunger.

In Fig. 1 there is shown a straight key-way 20 in the plunger, engaging which is a screw-key 21. This provides straight reciprocatory movement of the plunger. In Fig. 2 I show a construction particularly applicable to the thumb plunger, due to the fact that it is somewhat more difficult to turn the thumb than it is the fingers of the glove. A spiral key-way 22 is cut in the plunger and a collar 23, adaptable of being rotated to different circumferential positions in the enlarged bore 12 of the housing, carries the screw-key 21 which engages the key-way 22 and imparts a twisting movement simultaneously with the reciprocatory movement of the plunger.

The action of this twisting effort of the plunger on the glove thumb end is somewhat analogous to that of wringing a cork into a bottle to more easily seat it therein.

Were it not possible to move the screw-key 21, in Fig. 2, to different circumferential positions, then on making adjustments of the plunger, varying its vertical and inert position within the housing, the relation between the turning head 19 and the glove-support would not be constant. In other words, to hold the turning-head 19 so that in any one of various positions (as in Fig. 1) its flat sides will always point in the same direction, horizontally, then the screw-key must, at different times, engage different portions of the length of the key-way 22. This screw-key cannot, therefore, be located in the housing as a fixture, as is the same element in Fig. 1, but must be susceptible of circumferential movement 95 with respect to the housing so as to accommodate itself to any change in the vertical location of the plunger when at rest,—or when the nut 14 abuts on the cap 13.

To fixedly secure the collar 23, carrying 100 the screw-key 21, in any predetermined position the set-screw 24 is provided.

In Figs. 5 and 6 I illustrate my improved glove-finger support incorporating features which make it particularly adapted for use 115 on the fore and little fingers of the glove. The construction of the extreme upper end of the support is similar to that disclosed in my Patent No. 1,537,794, hereinbefore referred to, but in all other characteristics there are 120 marked dissimilarities.

Mounted on the lower bracket 2 of the machine are the four glove-finger supports and the glove-thumb support, the blades of the latter being preferably made as shown in Fig. 7. It will be understood that these glove supports fixed on the stationary lower bracket of the glove-turning machine operate in co-aktion with the yieldingly mounted glove plungers on the movable upper bracket.

Each of the glove support unit assemblies comprises a pedestal 25 having inclined sides 26 which bear on the similarly inclined surfaces 27 of the slot 28, which latter runs length-ways of the bracket and is of sufficient length to include the four supports when separated to their maximum center distances. A bolt 29 depends from the pedestal and on its lower end, which extends beyond the depth 5 of the bracket, is a nut 30 and washer 31. By these means each pedestal may be independently secured to the bracket and may also be moved therealong by releasing the nut 30. This feature of adjustability of the pedestals to obtain different center to center positionings thereof is very advantageous as it provides for the turning of a variety of sizes 15 of gloves with the least amount of labor involved in re-positioning the parts so as to accommodate each respective size of the glove 20 to be turned.

The upper end of the pedestal is bifurcated and between the ears 32 the swing-block 33 is journaled over the pin 34. A downwardly 25 extending portion 35 of the swing-block contacts with one end of the helical spring 36 which is disposed in a hole 37 in the pedestal. A screw-plug 38 on which the opposite end of the spring abuts serves, when screwed in 30 or out of the hole, to increase or decrease the tension of the spring.

On the upper opposite side of the swing-block is a horizontal arm 39 in which is the adjusting screw 40,--the latter contacting 35 with the pedestal at 41. By actuating this screw 40 the support may be placed in various upright positions, either perpendicular or inclined to either side thereof.

Rising from the swing-block 33 is a shank 40 42 screw-threaded to receive the glove-support holder 43 which carries the glove-support blades 44.

After continued use, especially in the operation 45 of turning heavy, stiff gloves, these glove-support blades often become bent or otherwise unfit for service. This requires replacements and I have provided in my improved construction a simple method of attaching the blades to the holder. In fact I have illustrated two quick detachable designs, either 50 of which I have found satisfactory.

In Figs. 5 and 6 I show the side and end views and in Fig. 11 a transverse section through one of these blade holding structures. 55 The holder 43 has a reduced portion 45 and in this portion is bored a taper hole to receive the taper pin 46. A diagonal scarf 47 is cut through the reduced portion and a square sleeve 48 mounted thereover, the shanks of 60 the blades being interposed, one on each transverse side of the holder. A slight drive of the pin 46 will lock the parts together.

In the modified form of the holder shown 65 in Figs. 8 and 9, the body of the holder is milled at opposite sides to receive the thick-

ness of the blades and a square hole 49 made to allow the ears 50 of the blades to enter. A block 51 separates the ears and a taper pin 52 extends through all the parts,--the holes through the ears being somewhat elongated 70 so as to allow the pin to bear strongly on one end of the hole, thereby pulling it into the holder with a strong wedge-like action. The holder is screw-threaded at its lower end so as to be mountable over the shank 42, the 75 tapped hole being at 53.

On my previously patented glove-turning machine, previously referred to, I employ gripping members which grasp the wrist-band of the glove on the upward stroke of 80 the movable bracket and pull the glove off the glove-supports.

To facilitate the operation of gripping the glove I provide means to hold the wrist-band outwardly of the support blades so that the 85 grippers may more easily engage it. To this end I insert between the blades a fender 54 which, like the blades, lies interjacent the scarfed portion 45 and the outer sleeve 48. Thus by the expansion of the split portion of 90 the holder 43 caused by the forcing of the taper pin 46 into the hole in the holder, all three members,--the two blades 44 and the fender 54 are firmly locked to the holder.

The fingers of a glove lie substantially in 95 the same plane, but the thumb inclines outwardly somewhat. It is therefore more difficult when mounting a glove over the supports to procure an easy entrance of the thumb than the finger supports in their respective openings in the glove. This is particularly true in the case of wrist-band gloves which usually come to the machine with the 100 wrist-bands turned inwardly and upwardly within the glove space,—often so far upwardly that the thumb opening is closed.

I largely overcome this trouble by curving the thumb-support blades inwardly, as seen in Figs. 7 and 7^a. The operator is then able to draw the glove downwardly and inwardly 105 of the top of the support which has the effect of giving the thumb a slight transverse, inward movement effecting an easier entrance of the end of the support into the thumb opening.

The vertical adjustment features of the 110 glove plungers have already been dealt with. Those effecting the glove supports comprise the vertical adjustment of the holders 43 on the shanks 42,—a check-nut 55 serving to lock 115 the holder in any adjusted position. Also, the tilt or incline in which the outer glove supports are held in normal position is taken care of by the adjusting screw 40 which positively holds the support against movement in one direction,—the compression of the 120 spring 36 allowing the support to oscillate in the opposite direction. Both plunger and support units are manually adjustable to different positions on their respective brackets. 125

Having thus described my invention, what I claim is:

1. In a glove-turning mechanism comprising in combination with a glove-finger support, an oscillatory holder for said support, resilient means adapted to resist the oscillatory movement of said holder, and means to vary the normal, inert position of said holder whereby said glove-finger support may be placed in different upright positions, either in or on either side of perpendicular.
2. In a glove-turning mechanism comprising in combination, a vertically fixed glove-finger support, a yieldingly mounted glove-finger plunger adaptable of engagement with a glove positioned over said support, and means to rotate said plunger on its axis while thus engaged.
3. In a glove-turning mechanism comprising in combination a glove-finger support including two resilient blades therefor, a holder adapted to receive said blades, a fender disposed between said blades mounted on said holder, and a taper-pin acting to secure said blades and said fender to said holder.
4. In a glove-turning mechanism for glove-turning machines comprising in combination, a fixed bracket, a plurality of glove-finger supports mounted on said bracket, means to locate said supports in various longitudinal positions on said bracket, and a curved, double-blade glove-thumb support on said bracket, the convex edges of said curved blades being adjacent said glove-finger supports.
5. In a glove-turning mechanism, comprising in combination a vertically reciprocable bracket, a housing mounted on said bracket, a plunger in said housing, means to locate said plunger in various normal, inert vertical positions in and relative to said housing, and yielding means acting to force said plunger downwardly from said housing while disposed in any one of the said various normal, inert positions in which it may be located.
6. In a glove-turning mechanism comprising in combination, a fixed bracket having a longitudinal slot therein, a pedestal mounted on said bracket, means to secure said pedestal in various longitudinal positions on said bracket, a swing-block oscillatively journaled in said pedestal, yielding means acting on and tending to rotate said swing-block in one direction, means to restrict and limit the action of said rotating means, and means whereby said swing-block may be held against rotation in various inert positions in and relative to said pedestal.
7. In a glove-turning mechanism for glove-turning machines comprising in combination a fixed bracket having a slot running lengthwise therethrough, a plurality of pedestals arranged along the top of said bracket, means to fixedly secure said pedestals in various positions on and longitudinally of said fixed bracket, a swing-block oscillatively jour-

naled in each of said pedestals, a glove support, including two laterally resilient blades, a blade holder, means to secure said blades to said holder, a shank on said swing-block, and means to adjustably secure said holder in various vertical positions on and relative to said shank.

8. In a glove-turning mechanism for glove-turning machines comprising in combination a fixed bracket having a longitudinal slot therethrough, a plurality of glove supports on said fixed bracket, a reciprocable bracket having a longitudinal slot therethrough, a plurality of housings on said reciprocable bracket, a plunger in each of said housings, means whereby said plunger may be located in various vertical, inert positions in and with respect to said housings, and means to locate said plungers and said glove-supports in various center to center positions on their respective brackets whereby when alignably assembled in any one of the said various positions said plungers and said glove-supports may, on the descent of said reciprocable bracket, mutually engage in mating order.

9. In apparatus of the class described comprising in combination with an expandible, tubular glove-finger support, a plunger housing, a plunger reciprocable in said housing and adapted to engage the tip of a glove finger mounted on said support, a key-way in said plunger, a key in said housing engaging said key-way, a spring tending to force said plunger from said housing toward said support, means to locate said plunger in various axial positions in said housing and hold it normally inert against the action of said spring, and means whereby the expandible force of said spring acting on said plunger may be made to remain the same in whichever axial position, relative to said housing, said plunger may be located and inertly held therein.

In testimony whereof I affix my signature.

DAVID BAUM.
